(57) **CLAIM**

The ornamental design for an automobile body and/or replica, as shown and described.

DESCRIPTION

FIG. 1 is a rear elevation view of an automobile body and/or replica showing our new design with the door panels in open position;

FIG. 2 is a right side elevation view thereof;

FIG. 3 is a left side elevation thereof;

FIG. 4 is a front elevation view thereof;

FIG. 5 is a top plan view thereof;

FIG. 6 is a left, rear perspective view thereof;

FIG. 7 is a left, front perspective view thereof;

FIG. 8 is another left side elevation view thereof with the door panels in closed position;

FIG. 9 is a rear elevation view of FIG. 8;

FIG. 10 is a front elevational view of FIG. 8;

FIG. 11 is a rear elevational view of FIG. 8;

FIG. 12 is a left, front perspective view of FIG. 8;

FIG. 13 is a top plan view of FIG. 8; and,

FIG. 14 is a left, rear perspective view of FIG. 8.

The wheels shown in broken lines are for illustrative and environmental purposes and form no part of the claimed design.
